UNITED STATES PATENT OFFICE.

FRANKLIN E. ARNDT, OF GALION, OHIO, ASSIGNOR TO THE GALION IRON WORKS & MFG. CO., OF GALION, OHIO, A CORPORATION OF OHIO.

STONE SPREADER.

Application filed October 12, 1921. Serial No. 507,202.

To all whom it may concern:

Be it known that I, FRANKLIN E. ARNDT, a citizen of the United States, residing at Galion, in the county of Crawford and State 5 of Ohio, have invented certain new and useful Improvements in Stone Spreaders, of which the following is a specification.

This invention relates to road making machinery, particularly to devices for spreading so called road "metal," such as crushed rock, gravel and the like upon a roadway.

I am aware of the existence of devices for this purpose but they all appear to possess a serious drawback. Such devices are ordinarily provided with runners and are trailed behind a truck which dumps the material into a hopper from which the material discharges on to the roadway and is placed thereon to a certain predetermined depth. The width 10 of these devices is ordinarily approximately six feet and it is therefore necessary to make several trips along the roadway in order to cover the entire surface thereof with the material. In the ordinary spreaders this results in leaving a furrow between the successive covered strips of road and these furrows must subsequently be filled by shoveling the material thereinto, this, of course, necessitating manual labor and involving 15 considerable expense. It is the overcoming of this objection which constitutes one of the essential objects of the present invention which contemplates the provision of a spreader having its supporting runners spaced inwardly from the ends so that the successive paths of movement of the device along the roadway may be overlapped to avoid the formation of such a division furrow.

Another object is the provision of novel means for adjusting the height of the discharge hopper with respect to the supporting runners whereby to vary the depth of the layer of material spread upon the road, this adjusting means being provided at both sides of the hopper and being independently operable at each side whereby one side may be elevated to a greater extent than the other for the purpose of tilting the hopper so that the layer of material spread will be thicker at one side than at the other so that a crowned road may be formed.

The invention further resides in the provision of certain details of construction of

the hopper and its mounting whereby the adjustment will be facilitated, it being furthermore a feature that the construction is comparatively simple and inexpensive while at the same time the machine will be extremely efficient and durable.

To the attainment of the foregoing the invention consists in the details of construction and arrangement of parts to be herein-after more fully described and claimed, and illustrated in the accompanying drawings, in which:

Figure 1 is a side elevation of my device; Figure 2 is a front elevation with parts broken away and in section;

Figure 3 is a cross sectional view on the line 3—3 of Figure 1; and

Figure 4 is a sectional view on the line 4—4 of Figure 2.

Referring more particularly to the drawings; I have shown my device as comprising a hopper designated broadly by the numeral 10 and formed of end frames 11 consisting of a lower angle bar 12, a rear upright angle bar 13, a forwardly and downwardly inclined upper angle bar 14 and a forward angle bar 15 which is inclined rearwardly and downwardly. These end frames are covered with metal sheets 16 such as sheet steel of suitable gauge. The hopper further includes a rear wall 17 which is secured to the frame bars 13 and which is reinforced by upper and lower angle bars 18 and 19 respectively. The top and bottom of the hopper are open and the lower portions of the bars 15 have secured thereto a plate 20 which extends to the bottom but which terminates at substantially the centers of the bars 15.

In order to support the hopper I provide a pair of runners 21 which are L-shaped and which are spaced inwardly from the ends of the hopper, as clearly shown in Figure 2. Secured upon the top of the horizontal portion of each runner is a forwardly and upwardly inclined bracket 22 which extends to the upper forward edge of the hopper and this bracket is slidably engaged by guides 23 secured upon the plate 20. Secured to the upper end, that is the vertical arm of the runner, is an angular bracket 24 to which is secured one flange of an angle bar 25, to the other flange of which is secured the upper end of a deflector plate 26 which is here shown as being provided at its edges

with filler strips 27 and retaining plates 28 co-operating with angle bars 29 located at the forward corners of the hopper. This deflector plate 26 extends inwardly of the plate 20 of the hopper in overlapping relation thereto so that when the hopper is in its lowermost adjusted position there will be no gap between the plates 20 and 26.

In order that the hopper may be adjusted 10 so as to regulate the height of its bottom above the ground, I provide an inverted U-shaped bracket 30 at each upper forward corner of the device, these brackets being secured to the angle bar 25. Journaled 15 through each bracket is a shaft 31 provided outwardly of the bracket with an operating crank handle 32 and provided at its other end with a bevel pinion 33. Journaled 20 through each angle bracket 24 is a shaft 34 carrying a bevel pinion 35 meshing with the pinion 33. This shaft 34 passes slidably through the arms 36 of a bracket 37 secured upon the plate 20 at each side of the hopper. This end of the shaft 34 is threaded and 25 carries a nut 38 which is non-rotatably mounted between the bracket arms 36.

Secured to the vertical arms of the runners are angle plates or brackets 39 provided with a series of holes 40 within any one of 30 which may be inserted a bolt 41 with which is associated a draft bar 42 carrying a clevis 43 for attachment of a draft chain or the like by means of which the device may be drawn along a roadway.

35 Assuming that the device has been constructed and assembled as above described, the operation is as follows: The machine is trailed along a roadway behind a dumping truck, by means of draft chains or the like 40 hitched to the clevises 43. Road material such as crushed stone, gravel or the like is constantly discharged from the truck into the hopper 10 and will of course pass through the latter and be discharged at the bottom thereof on to the roadway. The thickness of the layer of material spread by the device depends, of course, upon the height of the bottom of the hopper above the ground and this is regulated by turning the ground and this is regulated by turning 45 the crank handles 32 so as to rotate the shafts 34 by means of the gearing disclosed and these shafts being threaded through the nuts 38 will operate to move the brackets 37 up and down, as the case may be, this resulting in corresponding movement of the hopper. The plate 20 of the hopper slides under the deflector plate 26, as will be apparent, and owing to the overlapping of these plates there will never be any gap between 50 them regardless of the position of the hopper. In some instances, as in making a crowned road, it is desirable that one end of the hopper be higher than the other and this is readily accomplished by turning one of 55 the cranks 32 more than the other which will

result in tilting the hopper to one side or the other. It is of course necessary that there be sufficient play between the parts so as to prevent binding action which would prevent the tilting but this is a mere detail of the 70 construction.

One of the most vital features of this device is that the runners 21 are disposed inwardly of the ends of the hopper so that when the machine has been pulled along one 75 side of a road and has deposited a layer of material thereon and it is subsequently desired to run the machine along the other side of the road for completing the spreading operation, the path of the second trip 80 may overlap the path of the first trip, that is on the second trip the runners will travel along the uncovered roadway while the hopper will project beyond the path of the runner toward the edge of the material previously spread so as to discharge the material from the hopper immediately against the edge of the first applied layer so that no furrow will be formed between the successive covered strips, thus eliminating all necessity for manual shoveling and leveling. 85

From the foregoing description and a study of the drawings it will be apparent that I have thus provided a machine of simple construction and ready adjustment 90 which will efficiently operate to cover roads with any desired material to a uniform depth of thickness throughout, the device being furthermore adapted for forming a crowned road, the action in every instance 100 being highly efficient.

While I have shown and described the preferred embodiment of the invention it is of course to be readily understood that I reserve the right to make such changes in the form, construction and arrangement of parts as will not depart from the spirit of the invention or the scope of the subjoined claims.

Having thus described my invention, I 110 claim:

1. In a road material spreading device, a distributing hopper, and runners therefor located inward of the ends thereof, the end portions of the hopper beyond said runners being entirely unsupported with relation to the ground.

2. In a road material spreader, a distributing hopper, and ground engaging supports therefor disposed inward from the ends of the hopper, the ends of the hopper projecting beyond said supports being entirely unsupported from the ground whereby successive paths of travel of the hopper may be overlapped.

3. A road material spreading machine comprising a pair of runners, guide brackets carried thereby, a hopper having an open top and bottom, guides carried by the hopper and slidably upon the guide brackets,

stationary brackets extending from the hopper, nut members associated with said stationary brackets, threaded shafts extending through said nut members and gear operated means for rotating said shafts.

4. A road material distributing machine comprising a pair of ground engaging runners, inclined guides carried thereby, a hopper having an inclined front wall terminating short of the top thereof, a deflector plate rigidly supported from the upper ends of the runners and extending in slidable overlapping engagement upon the inner surface of the front wall of the hopper, guide brackets carried by the hopper and slidable along said guides, and means for moving the hopper with respect to the runners.

5. A road material distributing machine comprising a pair of ground engaging runners, inclined guides carried thereby, a hopper having an inclined front wall terminating short of the top thereof, a deflector plate rigidly supported from the upper ends of the runners and extending in slidable overlapping engagement upon the inner surface of the front wall of the hopper, guide brackets carried by the hopper and slidable along said guides, and means for moving the hopper with respect to the runners, said means comprising brackets rigidly secured to the front wall of the hopper and carrying non-rotatable nut members, shafts journally mounted with respect to the runners in advance of the hopper and having threaded engagement with the nut members, and means for rotating said shafts independently whereby to effect lateral tilting of the hopper.

6. A road material distributing machine comprising a pair of ground engaging runners, inclined guides carried thereby, a hopper having an inclined front wall terminating short of the top thereof, a deflector plate rigidly supported from the upper ends of the runners and extending in slidable overlapping engagement upon the inner surface of the front wall of the hopper, guide brackets carried by the hopper and slidable along said guides, means for moving the hopper with respect to the runners, said means comprising brackets rigidly secured to the front wall of the hopper and carrying non-rotatable nut members, shafts journally mounted with respect to the runners in advance of the hopper and having threaded engagement with the nut members, and means for rotating said shafts independently whereby to effect lateral tilting of the hopper.

7. A road material spreading machine comprising a pair of runners, upwardly and forwardly inclined guides carried thereby, a hopper having an inclined front wall extending upward from the lower end of the hopper and terminating short of the top thereof, a deflector plate operatively supported from the upper ends of the runners and extending in slidable, overlapping engagement with the front wall of the hopper, means slidably engaging the hopper with said guides, and means for adjusting the hopper along said guides and with relation to said runners.

In testimony whereof I affix my signature.
FRANKLIN E. ARNDT.
